UNITED STATES PATENT OFFICE.

CLARENCE E. BARR AND THOMAS E. JACKSON, OF DETROIT, MICHIGAN.

DESIGN FOR AN ELECTRIC TOASTER.

Application filed June 24, 1922. Serial No. 2,808. Term of patent 14 years.

To all whom it may concern:

Be it known that we, CLARENCE E. BARR and THOMAS E. JACKSON, citizens of the United States and of the Dominion of Canada, respectively, and residents of Detroit, in the county of Wayne and State of Michigan, have invented a new, original, and ornamental Design for Electric Toasters, of which the following is a specification, reference being had to the accompanying drawing, forming part thereof.

The drawing is a perspective view of an electric toaster embodying our present design.

We claim:

The ornamental design for an electric toaster, as shown.

CLARENCE E. BARR.
THOS. E. JACKSON.
